UNITED STATES PATENT OFFICE.

JULIUS MAKI, OF CHICAGO, ILLINOIS, ASSIGNOR TO THE WHELCO ENGINEERING & MANUFACTURING COMPANY, A CORPORATION OF ILLINOIS.

DOOR CONSTRUCTION FOR WASHING MACHINES.

Application filed October 20, 1927. Serial No. 227,372.

The present invention relates to wooden washing machines of the type disclosed in my prior Patent No. 1,598,355 and has for its object to improve the door construction in the 5 rotatable cylinders of such machines.

In machines of the character under consideration the wood around the door openings and in the doors wears, so that in time there may be formed cracks wide enough to allow 10 small pieces of wash to pass through or be caught and subsequently torn. Specifically considered, the present invention has for its object so to construct the doors and what may be termed the door frame that this objection 15 will be completely overcome.

The various features of novelty whereby my invention is characterized will herein-after be pointed out with particularity in the claims; but, for a full understanding of 20 my invention and of its objects and advantages, reference may be had to the following detailed description taken in connection with the accompanying drawings, wherein:

Figure 1 is an elevation of a fragment of 25 a washing machine cylinder embodying my invention; Fig. 2 is an edge view of one of the lower doors, on a somewhat larger scale than Fig. 1; Fig. 3 is a section on an enlarged scale taken on line 3—3 of Fig. 1; Fig. 4 is 30 a transverse section through the cylinder on line 4—4 of Fig. 1, the scale being the same as that of Fig. 3; Fig. 5 is a section on the same plane as Fig. 4, showing a smaller fragment of the cylinder, and the upper door being 35 open and Fig. 6 is a perspective view of a fragment of the cylinder, showing the upper door closed and the lower door open.

Referring to the drawings, 1 represents a wooden washing machine cylinder of any 40 usual or suitable construction and having any desired number of compartments each provided with a door opening in the periphery of the cylinder. My invention has to do with the cylinder closures and it will therefore be sufficient to describe only one of such closures.

The cylinder as a whole is made of parallel staves extending longitudinally of the cylinder, and the door opening is formed by the 50 removal of sections of the staves. As in my aforesaid patent, the door opening is provided with a closure, consisting of a wide upper door 2 and a narrow lower door 3. The upper door is hinged to a heavy wooden beam

4 forming the upper member of the door frame, and the lower door is hinged to a similar beam 5 bounding the door opening at the bottom.

As in my aforesaid patent, the upper door has parts 6 projecting beyond the free or lower edge to the lower door frame member, these parts underlying the lower door when both doors are closed. Also, the lower door is provided with catches 7 remote from its hinge axis to engage with the body of the 65 cylinder and lock the two doors in their closed positions.

Since the doors and the cylinder are made of wood, the gradual wearing away of the wood in service produces a looseness whereby 70 cracks or crevices are created, permitting small pieces of wash to pass through or be caught and torn. Such wearing occurs on the faces of the beams 4 and 5 bounding the door opening. In order that wear at these 75 points shall be harmless, I form in that edge of each of the beams 4 and 5 that meets the hinged edge of the corresponding door a deep narrow groove extending the entire width of the door, as indicated at 8 and 10. On the underside of the upper door I fasten a metal plate 9, preferably of brass that projects rearwardly beyond the edge of the door and enters the groove 8 when the door is closed; and the lower door is provided on its inner 85 side with a metal sheathing 11 projecting rearwardly beyond the hinged edge in position to enter the groove 10 when the door is closed. Consequently, no matter how great the wear on the beams, the joints between the 90 cylinder and the hinged ends of the doors will always remain tight, since the sealing grooves are deep and the plates on the doors preferably bottom in the same.

The lower door is used as an unloading 95 shelf and therefore, in order to protect it against wear, the metal preferably covers the entire inner face or side so as to form a complete sheathing for the same. Furthermore, I prefer to place on the lower beam 5, between the groove and the outer face of the beam a wearing plate 12 that will prevent the beam from wearing in this zone to a degree that will permit wash to catch when drawn out of the cylinder over the unloading door or shelf, or small pieces of wash to drop 100 down between the cylinder and the lower door.

I also provide the upper door with a metal lip 13 extending across the full width thereof at the front or free end, this lip projecting forwardly in about the plane of the under-
5 side of the door, to form a shelf on which the free end of the lower door rests when the doors are closed. The member 13 may conveniently be one flange of an angle member, the other flange of which is secured to and covers the
10 edge of the upper door. By this means there is not only formed a tight joint between the doors but, since the contacting faces between the doors are of metal, the tightness of the joint will be maintained in service, since the
15 metal will not wear appreciably.

As in my aforesaid patent, both doors are provided on their outer faces with metal plates, indicated at 14 and 15, respectively, to overlap the cylindrical walls of the cylinder at the sides of the door opening. As best shown in Figs. 1 and 3, the cylinder is sheathed with metal, as indicated at 16, in the zones engaged by the plates 14 and 15; the wooden body of the cylinder being made
20 of slightly smaller diameter immediately adjacent to the door opening, to compensate for the thickness of the metal sheathing 16. Therefore, when the doors are closed, there will be metal to metal contact between the
25 doors and the cylinder at the sides of the doors, thus preventing appreciable wear in service and insuring that the joints between the doors and the cylinders, at the sides of the doors, will always remain tight.

35 While I have illustrated and described with particularity only a single preferred form of my invention, I do not desire to be limited to the exact structural details thus illustrated and described; but intend to cover
40 all forms and arrangements which come within the definitions of my invention constituting the appended claims.

I claim:—

45 1. In combination, a horizontal washing machine cylinder having a door opening in its cylindrical wall, an upper door and a lower door associated with said opening and hinged respectively at the top and at the bottom, each door having at its hinge edge a fin pro-
50 jecting outwardly from said edge, and there being in the upper and lower edges of the wall bounding said opening deep grooves to receive said fins when the doors are closed.

55 2. In combination, a horizontal washing machine cylinder having a door opening in its cylindrical wall, wooden beams bounding said opening at the top and at the bottom, each beam having a narrow groove extending lengthwise thereof in the face directed to-
60 ward said opening, doors hinged to the respective beams, and metal fins on said doors

in position to enter said grooves when the doors are closed.

3. In combination, a horizontal washing machine cylinder having a door opening in its cylindrical wall, wooden doors respectively hinged to the cylinder at the upper and lower margins of said opening, the upper door having at its lower end a metal plate projecting outwardly from said edge on the inner side of the door, and the lower door having on its inner side a metal sheathing adapted to rest on said plate when the doors are closed.

4. In combination, a horizontal washing machine cylinder having a door opening in its cylindrical wall, a wide wooden upper door and a narrow wooden lower door respectively hinged to the cylinder at the upper and lower margins of the door opening, a metal facing on the inner side of the narrow lower door, and a lip of metal projecting from the lower edge of the upper door in position to underlie the lower door when the doors are closed, said lip being of a length substantially equal to the width of the doors.

5. In combination, a horizontal wooden washing machine cylinder having a door opening in its cylindrical wall, the bounding edges of the said wall at the top and at the bottom of said opening containing deep narrow grooves extending across said opening, metal strips on said wall at the sides of said opening, upper and lower wooden doors for said opening, a fin projecting from each door in position to enter the corresponding groove when the doors are closed, and metal elements projecting laterally from the doors in position to rest on said strips when the doors are closed.

6. In combination, a horizontal wooden washing machine cylinder having a door opening in its cylindrical wall, the bounding edges of the said wall at the top and at the bottom of said opening containing deep narrow grooves extending across said opening, metal strips on said wall at the sides of said opening, upper and lower wooden doors for said opening, a fin projecting from each door in position to enter the corresponding groove when the doors are closed, metal elements projecting laterally from the doors in position to rest on said strips when the doors are closed, a metal sheathing on the inner side of the lower door, and a metal lip projecting from the lower edge of the upper door in position to underlie the lower door when the doors are closed.

In testimony whereof, I sign this specification.

JULIUS MAKI.
